UNITED STATES PATENT OFFICE.

ARTHUR H. NUSSEY, OF PATERSON, NEW JERSEY, ASSIGNOR OF ONE-HALF TO
GEORGE C. BERDAN, OF PATERSON, NEW JERSEY.

SHADE-ROLLER BRACKET.

Application filed June 2, 1924. Serial No. 717,207.

To all whom it may concern:

Be it known that I, ARTHUR H. NUSSEY, a citizen of the United States, residing at Paterson, in the county of Passaic and State 5 of New Jersey, have invented certain new and useful Improvements in Shade-Roller Brackets, of which the following is a specification.

This invention has for its object to provide means to support a window shade which may be attached to an upper window sash so that when the sash is lowered the shade will be lowered therewith and will therefore not obstruct the opening formed by lowering the sash, said means being so constructed that parts which would otherwise interfere with the lower sash when one sash is to pass the other (as in cleaning the glass in the sashes) may be readily detached.

20 In the drawing,

Fig. 1 is a front inside elevation of a fragment of a window, showing a shade roller bracket constructed according to my invention in place on the upper sash;

25 Fig. 2 is a horizontal sectional view of the window frame and upper sash, showing the lower sash and the shade and the two brackets supporting the latter in plan;

30 Fig. 3 is a vertical sectional view of what is shown in Fig 1; and

Figs. 4 and 5, respectively, are a plan view of the bracket with its members separated and a front elevation of the fixed member.

35 In the drawing the window frame is indicated at *a*, the upper sash and lower sash being indicated at *b* and *c*, respectively. *d* is the shade roller and *e* the shade wound thereon; the shade roller is of the spring-roller type and will have as usual a round trunnion at one end and a flattened trunnion at the other, these trunnions being indicated at *d'*.

40 To each side rail of the upper sash *b* and to the inner face thereof and near the top rail is secured by screws *f* a plate *g* which projects beyond the inner edge of the rail as shown in Figure 4 and has extensions *g'* curved rearwardly substantially into the form of hooks, the same rigidly securing in place a vertical pin *h* which is generally cylindrical except that between the hooks and above and below them the material thereof is removed in a manner to leave flat faces *h'* arranged in a plane forming an

acute angle with the plate *g*; the pin is therefore as to the portions mentioned thinned.

An angular bracket is pivotally jointed by means of the pin *h* to the sash structure, here taken as including the sash proper and plate *g*. In the present case this bracket includes two sections. One section is a strip *j* of sheet metal bent transversely to substantially a right angle. One arm has three extensions at its free end which are curved, in the opposite direction to which the angle of the strip is formed, into the form of hooks *j'* adapted to fit around the pin *h*; these hooks form a pivot joint between the plate *g* of the sash structure and the section *j* of the bracket, the latter being adapted to swing from a position in which the arm thereof which has the hooks abuts and bears substantially against the plate *g* as shown by dotted lines in Figure 4. The other section of the bracket is a plain strip *k* provided with a suitable hole *k'* to fit the particular trunnion *d'* for which it is adapted. The section *k* is secured to the free arm of the section *j* of the bracket by a bolt *l* and nut *m* which clamps them together, said arm having a longitudinal slot *n* to permit adjustment of the section *k* lengthwise of said arm and the arm and section *k* having intermeshing vertical serrations as shown in figure 4 which, when the two parts are clamped up tight, insure the section *k* being maintained in the upright position.

The normal position of the parts is shown in Figure 2. Both brackets have the arms which afford the joints between them and the sash structure abutting the latter (more specifically, the plates *g*), each being held from swinging inwardly from this position by the shade roller whose trunnions are then engaged in the holes *k'* of the sections *k* of the brackets and each bracket being prevented from sliding inwardly, independently of the shade roller, because the entrance to each hook *j* is narrower than the major width of the pin then presented. If the upper sash is then lowered, as shown in Figure 1, the shade will be lowered with it and so leave a clear opening above the sash as shown at Figure 1. The brackets of course project into the path of movement of the lower sash and will therefore be an obstruction to either sash passing the other, as when the windows are to be washed. There-

fore the brackets may be removed from the upper sash structure as follows: having removed the shade roller, each bracket is swung inwardly to about the angular position indicated in Figure 4, whereupon the bracket is then shifted toward the glass *b'* of the sash to clear the hooks *j'* from the pins *h* which is possible because the minor thicknesses of the pin are now properly presented for this purpose.

Having thus fully described my invention, what I claim as new and desire to secure by Letters Patent is:—

- 15 1. In combination, a sash structure and a bracket formed angular in a horizontal plane and adapted to support on one arm thereof a shade roller arranged at the same side of said arm as the other arm projects therefrom, said bracket having its second-named arm pivotally jointed to the sash structure and thereby pivotally movable in a horizontal plane and having the relatively

outer face thereof adapted to abut said structure when the arm is swung in one direction and being then interlocked by the joint to said structure against detachment therefrom but being detachable from said support at the joint when the shade roller is removed upon swinging the bracket in the opposite direction.

20 2. A shade roller supporting means including a fixed member adapted to be secured to a supporting surface and an angular bracket having one arm pivotally jointed to said member and adapted to be swung in one direction against the same, the other arm of the bracket then projecting from said surface and said bracket being then interlocked by the joint to said member against detachment therefrom but being detachable from said member at the joint upon swinging the bracket in the opposite direction.

30 In testimony whereof I affix my signature.

ARTHUR H. NUSSEY.
